VENTILATION CONTROLLING DEVICE FOR
CHICK BOXES

Herman J. Kneubuehl, Sterling, Ohio

Application August 10, 1949, Serial No. 109,461

10 Claims. (Cl. 119—19)

1

The invention relates to boxes for transporting baby chicks, and more particularly to means for controlling the ventilation of such boxes.

It is common practice to ship baby chicks by rail, truck or the like, in boxes formed of corrugated paper board or similar material. These boxes are ordinarily made of sufficient size to hold a hundred chicks and are generally divided by partitions into four equal compartments, each of which contains one-fourth of the chicks in the entire box.

These boxes are provided with openings in the outer end walls of each compartment, so as to provide sufficient air to prevent the chicks from smothering, and openings are also usually provided in the cover or lid for the box.

It frequently happens, during the transportation of chicks in such boxes, that in loading or unloading the same they may remain outdoors for a considerable period of time, or the boxes may be stored overnight in an unheated freight or express warehouse, often resulting in the loss or serious injury to a considerable number of chicks due to exposure to the cold.

When chicks, shipped in such boxes, become cold they huddle together against the inner partition walls in an effort to get away from the cold air entering through the openings in the end walls.

The present invention contemplates the provision of means operated by this movement of the chicks within the box for controlling the ventilation thereof.

It is an object of the invention to provide a chick box, of the general character above referred to, having means therein, adapted to be operated by the movement of the chicks toward the inner partition walls of the box, for closing off the openings in the end walls so as to prevent cold air from entering therethrough.

Another object is to provide means operated by the movement of the chicks toward the partition walls for closing the openings in the lid or cover of the box.

A further object is to provide a chick box of the character referred to having a platform fulcrumed upon the bottom of each compartment and provided with means for closing the openings in the end walls when the platform is tilted by the movement of the chicks thereon toward the partition walls.

A still further object is the provision of such a chick box in which the tilting of the platform in this direction will close the openings in the lid or cover of the box.

The above objects together with others which will be apparent from the drawing and following description, or which may be later referred to, may be attained by the construction hereinafter described in detail and illustrated in the accompanying drawing, in which;

Fig. 1 is a top plan view, with the lid or cover removed, of one complete compartment, and fragmentary portions of the other three compartments, of a chick box embodying the invention;

Fig. 2 a vertical, sectional view through one compartment of the box, with the lid or cover thereon, showing the improved ventilation controlling means in the normal or open position;

Fig. 3 a view similar to Fig. 2 showing the ventilating means in the operated or closed position; and

Fig. 4 a fragmentary, vertical, sectional view through the outer end portion of one compartment of the box, showing a modified form of ventilating device in the lid or cover of the box.

The chick box, in which the improved ventilating controlling mechanism is located, may be of usual and ordinary construction comprising the bottom wall 10, side walls 11 and end walls 12 having ventilating openings 13 therein.

The usual partition walls 14 are located in the box, dividing it into four equal compartments, one complete compartment being indicated at A and portions of the other three compartments being indicated at B, C and D.

The usual cover or lid 15 is provided for the box, having the depending rim flange 16 for engaging over the upper portions of the side and end walls of the box. If desired, the cover or lid may have ventilating openings 17 therein located over each of the four compartments of the box.

This much of the box is of conventional construction and no claim is made thereto excepting in combination with the ventilation controlling mechanism which will be later described.

The mechanism for controlling the ventilation of the box includes a platform 18, formed of corrugated paper board or other suitable material, located in the bottom of each compartment of the box and fulcrumed thereon, intermediate its ends, so that the platform may rock from the position shown in Fig. 2 to that shown in Fig. 3.

To provide the fulcrum for the platform a reinforcing strip 19, extending transversely of the platform, may be glued or otherwise attached to the under side of the platform and one or more relatively narrow strips 20, also of corrugated

paper board or the like, may be glued or otherwise attached to the under side of the strip 19, preferably at a point closer to the inner end of the compartment than to the outer end thereof, as best shown in Figs. 2 and 3.

For the purpose of preventing the platform from being longitudinally displaced within the compartment, tacks, small nails, staples or the like, as indicated at 21, may project through the underside of each fulcrum strip 20 so as to penetrate the bottom wall 10 of the box.

An upright flap 22 is formed at the outer end of each platform 18, being located against the inner side of the end wall 12, as best shown in Figs. 2 and 3, and provided with openings 23 adapted to register with the openings 13 in said end wall when the platform 18 is in the normal position with the outer end thereof resting upon the bottom of the box, as shown in Fig. 2.

A pad of excelsior not shown or the like may be placed upon the top of each platform 18 if desired, in the same manner that such a pad is usually placed upon the bottom of the box within each compartment, to form a floor covering for the baby chicks.

Under normal temperature conditions the baby chicks will be spread over the entire area of each platform, and since the fulcrum for the platform is located off center toward the inner end thereof, the greater weight on the platform will be on the outer side of the fulcrum so that the platform will be normally located in the position shown in Fig. 2, with the openings 23 in the flap 22 registering with the openings 13 in the end wall of the box so that air may freely pass therethrough.

In the event that the air passing through these openings is too cold for the chicks, they will crowd together at the inner end of the platform causing the same to rock to the position shown in Fig. 3, the flap 22 being slidably moved upward adjacent the inner side of the end wall 12, so that the openings 23 in the flap are moved out of alignment with the openings 13 in the end wall, as shown in Fig. 3, substantially closing the openings 13 and preventing the cold air from the outside from passing therethrough into the box.

When the chicks become sufficiently warm they will again spread out over the entire area of the platform, causing it to rock back to the position shown in Fig. 2 so that air may again freely pass through the openings 13.

If it is desired to provide openings such as shown at 17, in the lid or cover of the box, means may be provided for closing these openings simultaneously with the closing of the openings 13 in the end wall.

For this purpose a sheet 24 of corrugated paper board or the like, covering substantially the area of the lid or cover over each compartment, is connected at its inner end to the under side of the cover, as by staples or the like indicated at 25, and normally inclined downwardly therefrom as shown in Fig. 2.

This sheet 24 is provided with a plurality of openings 26, staggered relative to the openings 17 in the lid or cover. The outer, free end of the perforate sheet 24 may rest upon the inturned flange 27 fixed to or formed upon the upper end of the flap 22.

When the platform 18 is tilted to the closed position shown in Fig. 3, shutting off the openings 13 in the end wall of the box, the upward movement of the flap 22 will, through the inturned flange 27 thereon, move the free end of the sheet 24 upward, into substantial contact with the un-

der side of the lid or cover, as shown in Fig. 3, so that the openings 17 in the lid as well as the openings 13 in the end wall of the box are simultaneously closed.

In Fig. 4 is shown a slight modification of the ventilation in the lid or cover. The box and the platform with the associated parts may all be of the same construction as shown in Figs. 1 to 3, and the same reference numerals are applied thereto.

The lid or cover 15a however is slightly different in that instead of having perforations therein, a large opening 28 may be formed of cutting a flap 29 therefrom and bending the free end thereof 15 downward into contact with the flange 27 upon the upper end of the flap 22.

The flap 29 may be normally held in the position shown in Fig. 4 by any suitable insert between the same and the lid, such as an ear cut from the lid and turned down and out over the edge of the flap 29 as indicated at 30.

With the parts in the position shown in Fig. 4, air may freely enter through the openings 13 in the end wall and through the large opening 28 in the lid or cover. When the platform is tilted so as to raise the outer end thereof and move the flap 22 thereon upward to close the openings 13, the flap 29 will be moved up to the opening 28, substantially closing the same.

From the above it will be obvious that a simple and inexpensive mechanism is provided for controlling the ventilation of a chick box by the natural movements of the chicks, so that as the chicks become cold they will automatically close the ventilating openings in the box by huddling together at the inner end of the compartment, and as they become too warm they will automatically open the ventilating openings by spreading out over the entire area of the compartment.

I claim:

1. In a chick box having a bottom, side walls and perforate end walls, and partitions dividing the interior of the box into compartments, a platform fulcrumed intermediate its ends upon the bottom of each compartment and an upright flap at the outer end of the platform having openings therein arranged to register with the openings in the end wall when the outer end of the platform is tilted down and to be moved out of alignment when the platform is tilted in the opposite direction.

2. In a chick box having a bottom, side walls and perforate end walls, and partitions dividing the interior of the box into compartments, a platform fulcrumed intermediate its ends upon the bottom of each compartment, the fulcrum being at a point closer to the inner end of the platform than to the outer end thereof, and an upright flap at the outer end of the platform having openings therein arranged to register with the openings in the end wall when the outer end of the platform is tilted down and to be moved out of alignment when the platform is tilted in the opposite direction.

3. In a chick box having a bottom, side walls and perforate end walls, and partitions dividing the interior of the box into compartments, a platform fulcrumed intermediate its ends upon the bottom of each compartment, means preventing longitudinal movement of the platform within the compartment, and an upright flap at the outer end of the platform having openings therein arranged to register with the openings in the end wall when the outer end of the platform is tilted down and to be moved out of alignment.

ment when the platform is tilted in the opposite direction.

4. In a chick box having a bottom, side walls and perforate end walls, and a perforate cover, and partitions dividing the interior of the box into compartments, a platform fulcrumed intermediate its ends upon the bottom of each compartment and an upright flap at the outer end of the platform having openings therein arranged to register with the openings in the end wall when the outer end of the platform is tilted down and to be moved out of alignment when the platform is tilted in the opposite direction, and means for closing the perforate cover when the platform is tilted in said opposite direction.

5. In a chick box having a bottom, side walls, perforate end walls and a perforate cover, and partitions dividing the interior of the box into compartments, a platform fulcrumed intermediate its ends upon the bottom of each compartment, an upright flap at the outer end of the platform having openings therein arranged to register with the openings in the end wall when the outer end of the platform is tilted down and to be moved out of alignment when the platform is tilted in the opposite direction, and a sheet within each compartment connected at its inner end to the under side of the cover and having its outer free end resting upon the top of said flap for closing the perforate cover when the platform is tilted in said opposite direction.

6. In a chick box having a bottom, side walls, perforate end walls and a perforate cover, and partitions dividing the interior of the box into compartments, a platform fulcrumed intermediate its ends upon the bottom of each compartment, an upright flap at the outer end of the platform having an inturned flange at its upper end, and having openings therein arranged to register with the openings in the end wall when the outer end of the platform is tilted down and to be moved out of alignment when the platform is tilted in the opposite direction, and a sheet within each compartment connected at its inner end to the under side of the cover and having its outer free end resting upon the flange at the top of said flap for closing the perforate cover when the platform is tilted in said opposite direction.

7. In a chick box having a bottom, side walls, perforate end walls and a perforate cover, and partitions dividing the interior of the box into

compartments, a platform fulcrumed intermediate its ends upon the bottom of each compartment, an upright flap at the outer end of the platform having openings therein arranged to register with the openings in the end wall when the outer end of the platform is tilted down and to be moved out of alignment when the platform is tilted in the opposite direction, and a perforate sheet within each compartment connected at its inner end to the under side of the cover and having its outer free end resting upon the top of said flap for closing the perforate cover when the platform is tilted in said opposite direction.

15. 8. In a chick box having a bottom, side walls, perforate end walls and a perforate cover, and partitions dividing the interior of the box into compartments, a platform fulcrumed intermediate its ends upon the bottom of each compartment, an upright flap at the outer end of the platform having an inturned flange at its upper end, and having openings therein arranged to register with the openings in the end wall when the outer end of the platform is tilted down and to be moved out of alignment when the platform is tilted in the opposite direction, and a perforate sheet within each compartment connected at its inner end to the under side of the cover and having its outer free end resting upon the flange at the top of said flap for closing the perforate cover when the platform is tilted in said opposite direction.

20. 9. In a chick box having a bottom, side walls and a perforate cover, a platform fulcrumed intermediate its ends upon the bottom of the box, an upright flap at one end of the platform, a sheet connected at one end to the cover and operatively associated with said upright flap for closing the perforate cover when the platform is tilted in one direction.

25. 10. In a chick box having a bottom, side walls and a perforate cover, a platform fulcrumed intermediate its ends upon the bottom of the box, an upright flap at one end of the platform, and means upon the cover and operatively associated with said upright flap for closing the perforate cover when the platform is tilted in one direction.

HERMAN J. KNEUBUEHL.
